(57) CLAIM

The ornamental design for a garment, as shown and described.

DESCRIPTION

FIG. 1 is a front perspective view of a garment showing my new design;

FIG. 2 is a front view thereof;

FIG. 3 is a first side view thereof; and,

FIG. 4 is a second side view thereof.

The long-and-short broken lines form an unclaimed boundary around at least a portion of the claimed subject matter, do not exist in the article, and form no part of the claim. The even-length broken lines, which show the remainder of the article, are directed to environment, represent unclaimed subject matter, and form no part of the claimed design.
